GAS RANGE CONSTRUCTION

Filed April 16, 1927

2 Sheets-Sheet 2

UNITED STATES PATENT OFFICE.

HENRY MOECKER, JR., OF FLOSSMOOR, AND THEODORE THOMPSON AND OTTO HAMMERMEISTER, OF HARVEY, ILLINOIS, ASSIGNEES TO AMERICAN STOVE COMPANY, OF ST. LOUIS, MISSOURI, A CORPORATION OF NEW JERSEY.

GAS-RANGE CONSTRUCTION.

Application filed April 16, 1927. Serial No. 184,278.

This invention relates to improvements in gas range constructions and refers particularly to the construction of the splasher plates at the back and side of the open burner top.

In this art the splasher plate at the rear of the oven top is commonly known as the "splash back", while the splasher plate at the side of the open burner top is commonly known as the "splash side", this latter plate in reality comprising the outer wall at the inner side of the oven adjacent the open burner top. Usually these plates are enameled to enable the easy and ready removal of stains occasioned by the boiling over or splashing of food while in the course of being cooked on the burners of the open burner top.

The primary object of the invention is the provision of a splash back and splash side whereby the fastening of the splash back is at the rear of the range and the joining of the splash back and the splash side is both smooth and sanitary, as well as pleasing to the eye.

A further object of the invention is the provision of a novel form of construction at one end of the splash back whereby the connection between the splash back and the splash side is beveled, thus joining the members in a smooth and sanitary manner.

A still further object of the invention is the provision of a splash back of a construction whereby the splash back can be readily and quickly assembled and attached to the range and the range oven after the completion of the oven assembly.

Other further objects, novel features of construction and improved results of the invention will appear in the herein appended description and the accompanying drawings.

In the drawings:

Figure 1 is a fragmentary perspective view of a gas range showing the application of the improved invention.

Figure 2 is a fragmentary horizontal sectional view through the splash back, the splash side and the rear wall of the oven.

Figure 3 is a detail perspective view of the splash back, the splash side and rear oven wall, the parts being shown in unassembled or strung out relation.

Figure 4 is a vertical sectional view taken on the line 4—4 of Figure 2, looking in the direction indicated by arrow.

55

Referring to the drawings, A represents the oven, B the splash back, C the splash side, D the frame of the open burner top, E the top shelf and F the oven back.

Referring to the several parts and to the drawings in detail, it will be seen that the rear wall F of the oven is provided at its top with a flange portion 5 slightly inset from the main back portion 6 and that this flange is provided with bolt holes 7. The oven top 8 is provided with a downwardly extending peripheral flanges or edges 9 and the rear flange of the oven top is adapted to be bolted to said rear wall of the flange 5, with the oven top flange occupying the inset above referred to.

The side splash C has a main body portion 9 and is likewise provided at its inner end with an inset flange portion 10 terminating in a bend edge or flange 11 at right angles to the main body portion. The flange 11 is adapted to be positioned in the longitudinal flange 12 at the inner side of the back wall and be securely fastened thereto by means of a bolt 13 and nut 14. For the purpose of strengthening the connection between the splash side and the rear wall of the oven, the rear wall is provided with an edge 15 bent inwardly at right angles to the main body portion of the wall, as clearly appears in Figure 2 of the drawings.

80

The top of the burner frame D is supported to the range structure in any common well known manner and abuts the bottom edge of the splash plate as at 16, 90 a flange 17 being provided at the lower edge of the splash plate and provided with bolt hole openings 18 whereby this edge of the plate can be fastened to the burner top frame.

95

The back splash main body portion 19 is provided with offset flanges 20 and 21 at its upper and lower edges. These flanges are provided with openings 22 and 23 for the purpose of receiving bolts. The lower flange is bolted to the rear of the oven-top frame D while the upper edge is adapted for connection to the rear edge of the top shelf, by reason of its flange 24. Ad-

100

jaçent its inner end the back splash is tapered or beveled inwardly as appears at 25. The extreme end of the splash back is bent into an L shape, the legs of the L being designated as 26 and 27 respectively. The bend between the inward taper and the L is rounded as at 28 while the outer longitudinal end of the leg 27 is flared inwardly as at 29.

- 10 The L leg portion 26 is adapted to engage and seat within the flange 10 at the inner longitudinal edge of the splash side and this leg is of a length whereby the remaining leg portion 27 of the L is positioned in a plane parallel with but separated from the rear wall of the oven to provide a space 30 of a depth equal to the thickness of the nut 14 carried by the bolt 13 which fastens the splash side and oven back together.

By reason of this construction the oven back and splash side can be bolted together and the splash back later attached, the L leg 27 being provided with suitable openings to receive the outer end of the nut 13 and being clamped in place by a nut 31. When the nut 31 is turned down, the in-turned edge 29 will engage the rear of the oven and cause an outward tension to be placed upon the nut 31, thus in effect locking the nut against loosening.

As clearly appears in the drawings, the upper and lower flanges 20 of the splash back stop short of the inward bend where- 35 as the top shoulder 21 and also the lower shoulder 21 continue with the bend or taper, being designated at 32. The shoulder portion 32 is tapered with the bend and terminates at the rounded corner 28.

40 The shoulders or fins 32 greatly strengthen the splash back at its point of taper and additionally serve another purpose. The fin at the top of the splash back forms a continuation of the longitudinal support for 45 the top shelf E whereas the lower fin of the splash back engages the upper face of the corner of the open top burner frame D and supports the splash back bulged end portion. The end wall 33 of the top shelf 50 is adapted to be bolted to the down-turned edge 19 at the inner side of the oven top 8.

For the purposes of appearance, a shelf back 37 is provided which extends not only throughout the length of the top shelf but 55 also throughout the width of the oven top at the rear edges thereof.

By reason of the foregoing construction a flush connection or joint is formed between the splash back and the splash side 60 and a rounded corner is presented to the eye rather than a square corner. This greatly adds to the appearance of the stove and makes the stove much more sanitary as the splash plates are more easily cleaned. Additionally by reason of the construction de-

scribed, it is possible to attach the splash back and top shelf to the range after the oven has been assembled.

It will be readily seen that the back splash provides a simple and cheap manner of attaching the top shelf. The horizontal flange 21 of the splash back affords longitudinal support at the rear edge of the top shelf, while the upper fin 32 supports the rear inner corner of the shelf. The fin-shaped flanges additionally strengthen the bulged portion of the back plate so that the plate does not easily warp by reason of the heat from the cooking top burners and oven.

Having thus described our invention, what we claim is:

1. A range construction comprising a cooking top having an oven at one side and a splash plate at its rear, a beveled connection between the splash plate and the oven, and the bevel forming said connection being an integral part of said splash plate.

2. A range construction comprising a cooking top having an oven at one side and a splash plate at its rear, and said splash plate provided with an inwardly extending bulge adjacent its inner end, whereby a bevelled connection is provided between the splash plate and the oven.

3. A range construction comprising a cooking top having an oven at one side and a splash plate at its rear, said splash plate provided with an inwardly extending taper adjacent its end, said tapered portion adapted to provide a rounded corner at the junction of the splash plate and the oven, and said tapered portion provided at its upper and lower ends with a strengthening flange, for the purpose described.

4. A gas range construction comprising a cooking top having an oven at one side and a splash plate at its rear, said oven provided at its rear inner corner with a depression, the splash plate provided adjacent its end with an inwardly extending taper terminating in an L-shaped flange, and one leg of said splash plate flange adapted to seat within the oven depression, whereby the connection between said splash plate and oven is tapered and the splash plate and the oven wall are flush with one another.

5. A gas range construction comprising a cooking top having an oven at one side and a splash plate at its rear, said splash plate provided adjacent its end with an inwardly extending tapered bulge adapted for a flush connection with the oven, horizontal flanges at the upper and lower sides of said splash plate, said horizontal flanges terminating in vertical flanges, the upper flanges of the plate adapted to receive and support a top shelf, and the lower flanges of the plate adapted to engage the cooking top for supporting the plate in position.

6. A range construction comprising a

cooking top having an oven at one side and a splash plate at its rear, the inner side and back walls of said oven having overlapping bolted connection, the splash plate bent into 5 an L-shape at its end, one leg of said L adapted to engage the oven side and the other leg to parallel the oven back, and said last mentioned leg provided with openings to receive the oven bolts for the purpose of 10 fastening the splash plate in place.

7. A gas ranged construction comprising a cooking top having an oven at one side and a splash plate at its rear, said oven, side and rear walls bolted together by a 15 bolt extending outwardly therefrom at the rear of the oven, the splash plate bent into an L-shape at its end, one leg of the L adapted to parallel and engage the oven side and the other leg of the L to parallel the rear 20 wall of the oven, openings in said last mentioned leg for the passage of the oven bolts, and said last mentioned leg provided with an inwardly bent longitudinal end adapted to engage the rear of the oven for holding 25 the leg in separated parallel relation thereto.

8. A splash plate for the rear of the cooking top of an oven, comprising a main body portion having L-shaped flanges at its upper and lower edges, an inwardly extending 30 bulge adjacent one end of said plate, said bulge terminating in an L-shape bend, and the upper and lower edges of said bulged portion provided with a tapered flange positioned at right angles with the bulged portion, for the purpose described.

9. In a stove structure, a splasher plate for the back of the burner top, a splasher plate comprising the inner side of the oven, said back splasher provided with an inwardly 35 extending bulged tapered portion having flanges at its upper and lower ends, the oven plate provided with an inset adjacent its

inner end, the bulged portion of the back plate terminating in an L-shaped bend, one leg of which is adapted to seat within said 45 oven plate inset and the other leg to parallel the rear of the oven for connection therewith, the flange at the upper end of the bulge adapted to strengthen the plate at this point and provide support for a top shelf, 50 and the flange at the lower end of the bulge adapted to seat upon the cooking top for supporting and strengthening the back plate at its lower corner.

10. A range construction comprising a 55 cooking top having a side splash plate and a splash plate at its rear, said rear plate having an inward taper adjacent its end adapted for abutment with said side plate, whereby a rounded corner is presented at 60 the juncture of the plates.

11. A range construction comprising a 65 cooking top having an oven at one side and a splash plate at its rear, said splash plate provided with an integrally formed inwardly extending bulge adapted to abut the oven, whereby a beveled connection is provided between the splash plate and the oven.

12. A range construction comprising a 70 cooking top having a side splash plate and a splash plate at its rear, said rear plate having an integrally formed inwardly extending taper adjacent its end, said inward taper terminating in a wall at right angles 75 to the plate, and said wall adapted for abutment with said side plate, whereby a rounded corner is presented at the juncture of the plates.

In testimony whereof, we hereunto affix our signatures.
